CONTAINER FOR DAIRY PRODUCTS OR THE LIKE

Clara Virginia Eicholtz, Midland, Mich., assignor to The Dow Chemical Company, Midland, Mich., a corporation of Delaware

Filed Dec. 29, 1960, Ser. No. 63,384

Term of patent 14 years

(Cl. D58—17)

FIGURE 1 is an elevational view of a container for dairy products or the like, showing my new design;

I claim:

The ornamental design for a container for dairy products or the like, as shown.
